STACY B. HASELTINE, OF CHICAGO, ILLINOIS, ASSIGNOR, BY MESNE ASSIGNMENTS, TO
W. H. MINER, INC., A CORPORATION OF DELAWARE.

DRAFT RIGGING.

Application filed November 30, 1923. Serial No. 677,602.

This invention relates to improvements in draft riggings.

The object of the invention is to provide a simple and relatively inexpensive cushioning device, especially adapted for attachment to mine cars to effectively cushion the pull and draft shocks between the cars of a train.

In the drawing forming a part of this specification, Figure 1 is a top plan view of the end portions of two adjacent mine cars, showing my improvements applied thereto. Figure 2 is a vertical, longitudinal, sectional view taken centrally of the mine cars and corresponding substantially to the line 2—2 of Figure 1. And Figure 3 is a vertical, transverse, sectional view corresponding substantially to the line 3—3 of Figure 2.

In said drawing, each mine car is shown as provided with a suitable heavy flooring 10, a vertical end wall 11 at one end, and a horizontally pivoted gate 111 at the other end, the gate end of one car being disposed adjacent the closed end of the next car, as shown in the drawing. The flooring of each car is extended respectively beyond the end wall 11 and the gate 111 to constitute what may be termed either an end sill or a platform.

The improved draft rigging, as shown, comprises, broadly, upper and lower members A and B forming a two-part spring cage fixed to the closed end of each car; a spring resistance element C within the cage; a combined drawbar and yoke D coacting with the spring resistance; a coupling element E pivoted to the yoke; a pair of angle brackets F fixed to the gate end of each car; a hock coupling element G pivoted to each bracket; and buffering plates H—H.

The upper member A is in the form of a rectangular plate having a central, upwardly offset portion 12, longitudinally extending, spaced, downwardly projecting flanges 13—13, and a downwardly projecting transverse flange 14 at the rear end thereof the flanges 13 and 14 being aligned with the side walls and the end wall of the offset portion, thereby providing a casing forming a portion of the spring cage section. As clearly shown in Figure 1, the flooring 10 at the closed end of the car is provided with a recess or pocket 15 adapted to receive the spring cage section of the plate A. The plate A is also provided with downwardly extending flanges 16—16 at the front end

thereof adapted to abut the vertical end face of the platform or end sill portion of the flooring 10. The side flanges 13—13 snugly engage the side walls of the recess 15 and the flanges 14 and 16 abut the end wall of the recess and the front end portion of the flooring respectively. The lower member B is also in the form of a rectangular plate and is provided with longitudinally extending reinforcing ribs 17.

The plates A and B are provided at their front or outer ends with oppositely extending, aligned heavy flanges 18—18, with their free ends so spaced as to accommodate the shank of the drawbar D therebetween, as clearly indicated in Figure 2. Intermediate the flange 14 and the flanges 18, the two plates A and B are provided with another set of oppositely extending, aligned flanges 19—19 having their free edges separated a corresponding distance to the edges of the flanges 18 to accommodate the shank of the drawbar D. By means of the flanges 14, 19 and 18, two pockets are formed, the front one of which is somewhat longer than the rear one. Within the front pocket is disposed the spring resistance element C, the front end of the spring bearing upon the flanges 18 and the rear end of the spring bearing upon the flanges 19, in the normal position of the parts. The flange 19 of the plate A is braced by a longitudinally disposed web extending from the flange 19 to the flange 14 and the flange 19 of the plate B is braced by a similar rearwardly extending web abutting the flange 14 to transmit the buffering shocks from the flanges 19 through the flange 14 directly to the floor. The plate B is cut away at its upper side as

shown in Figure 2 to accommodate a transversely extending reinforcing bar 20. The members A and B forming the two-part spring cage are secured together and fastened to the car by bolts 21 extending through the plates and the flooring 10.

The combined yoke and drawbar D is formed at its outer or front end with a buffering head 22 defined by an upper heavy flange 23, a downwardly extending, transversely arranged flange 24, longitudinally extending spaced webs 25—25, a bottom flange 123 extending from each web 25 to the corresponding side of the head and a short vertically disposed flange 124 at the back of the head extending laterally from each web 25. The

- webs 25 and the flange 24 define a pocket in which the coupling element E is pivotally supported by a pivot pin 26 extending through the webs 25 and retained in position by cotter pins. The flange 24 of the buffing head is formed with a flat front face and has the opposite ends thereof rounded as shown to properly coat with the buffing plates H of the adjacent car when the cars are traveling over a curved section of track. Rearwardly of the buffing head of the drawbar D, a rectangular yoke is formed, the same having side arms 27-27 and an end section 28 extending between the ends of the arms. Between the end section 28 and the buffing head D, the drawbar is provided with a relatively heavy transverse web 29 defining the front end of the center opening of the yoke. The center opening of the yoke corresponds in length to the distance between the flanges 18 and 19 and the spring C is accommodated within the same. As clearly shown in Figure 3, the end section 28 and the web 29 of the yoke are cut away centrally and the flanges 18 and 19 are correspondingly formed so as to interfit with the same, thereby providing abutment surfaces on the yoke and spring cage of substantially equal extent for each end of the spring resistance.
- 30 The coupling element E is provided with an eye 30 adapted to freely receive the hook portion of the coupling element G. The coupling element E is adapted to swing in a vertical plane and the flange 24 is centrally recessed to accommodate the same in horizontal position. Upward movement of the coupling element E is limited by engagement with the upper wall of the recess of the flange 24.
- 40 The angle brackets F are of like construction, each comprising an upper arm 31 and a downwardly projecting flange 32. The gate end of the car is provided with a recess or pocket 33 adapted to receive the flanges of the angle plates F in spaced relation so that the hook coupling element G may be accommodated between the flanges. The flanges 32 are shorter than the upper arm portions of the angle brackets and depend below the flooring 10 of the car.
- 50 The buffing plates H are of like construction and are in the form of U-shaped members, having upper and lower horizontal arms 34 and 35 and a vertically extending connecting section 36. The arms 34 and 35 are adapted to abut the upper and lower surfaces of the projecting portion of the flooring 10 and the vertical section is adapted to abut the front end of the flooring. The buffing plates H and the angle brackets F are secured by means of bolts 37 extending therethrough and through the flooring 10. The rear ends of the angle brackets F are secured to the flooring of the car by means of bolts 38 extending through the arms 31

thereof and reinforcing plates at the lower and filler plates at the upper side of the flooring.

The hook element G is pivotally supported for vertical swinging movement between the flanges 32 of the brackets F by means of a pin 39. The engaging end of the hook G is provided with a relatively long, pointed extension 40 which is bent outwardly as clearly shown in Figure 2, thereby preventing accidental disengagement of the hook from the eye portion of the coupling member E.

The normal position of the parts is as shown best in Figure 2, and upon draft action, it is obvious that the spring C will be held at its front end against the flanges 18 and the rear end thereof will be pulled forwardly by the rear transverse section 28 of the combined drawbar and yoke. In buff, the rear end of the spring C will be held by the flanges 19 and the forward end thereof moved rearwardly by the front section of the yoke, thus adapting the rigging to cushion both buff and draft shocks. In the buffing action of the mechanism, the buffing plates H of one car will directly engage the buffing head of the drawbar, thereby forcing the yoke inwardly relatively to the spring cage A-B. The parts are preferably so designed that the rear face of the portions 23 and 124 of the buffing head will engage with the front ends of the plates A and B to limit the inward movement of the combined drawbar and yoke when the mechanism has been fully compressed, thereby preventing the spring from being driven solid and transmitting the buffing shocks directly through the buffing head and the plates A and B to the car.

The arrangement which I have shown and described consists of few parts, all of which may be manufactured comparatively cheaply and the entire arrangement may be readily applied to mine cars of common construction now in use at small expense.

I have herein shown and described what I now consider the preferred manner of carrying out my invention but the same is merely illustrative and I contemplate all changes and modifications that come within the scope of the claims appended hereto.

I claim:

1. In a draft rigging of the character described, the combination with upper and lower plates, each provided with a plurality of flanges defining two pockets between the plates, said plates being adapted to be rigidly secured to a vehicle; of a spring within one of said pockets; a yoke slidably mounted between said plates and encircling said spring, said yoke having shoulders rigid therewith adapted to cooperate with the outer edge of one of said plates to limit the compression of the spring in buffing action.
2. In a draft rigging, the combination with

- the end structure of a car including a floor provided with a central recess; of a spring cage comprising co-operating castings having extensions secured to the opposite surfaces of said floor and provided with central portions enclosing said recess, said castings having integral flanges at opposite ends thereof extending toward each other and providing front and rear walls for said cage, 5 the extremities of the flanges forming the front and rear walls being spaced apart; spring means arranged between said front and rear wall; and a yoke encircling said spring means, the forward and rear ends of 10 said yoke being movable in opposite directions past the adjacent walls to compress said spring means on both buff and draft. 15
3. In a draft rigging, the combination with the end structure of a car including a floor provided with a central recess; of a spring cage comprising co-operating castings having extensions secured to the opposite surfaces of said floor and provided with central portions enclosing said recess, said castings 20 having integral flanges at opposite ends thereof extending toward each other and providing front and rear walls for said cage, the extremities of the flanges forming the front and rear walls being spaced apart; 25 spring means arranged between said front and rear wall; and a yoke encircling said spring means, the forward and rear ends of said yoke being movable in opposite directions past the adjacent walls to compress 30
- said spring means on both buff and draft; 35 a buffer on said yoke; and a coupling element pivotally mounted on said buffer and adapted to be normally disposed inwardly of the outer extremities of said buffer and to be moved outwardly of said buffer to operate position. 40
4. In a draft rigging for a railway car, the combination with yieldable means; of a cage secured to the end of said car and disposed about said yieldable means, said cage having 45 oppositely disposed portions extending to within the planes defined by the boundaries of said yieldable means to provide stationary abutments for the opposite ends of said yieldable means; yoke means encircling said yieldable means, said yoke means being arranged for movement in opposite directions to opposite sides of said stationary abutments to compress said yieldable means in both buff and draft, said yoke means being 50 provided with rigid portions projecting forwardly of the end of the car; a buffer secured to said forwardly projecting portions; and a coupling element pivotally mounted on said buffer and adapted to be normally disposed inwardly of the outer extremities of said buffer and to be moved outwardly of said buffer to operative position. 55

In witness that I claim the foregoing I have hereunto subscribed my name this 22nd 60 day of November 1923. 65

STACY B. HASELTINE.
